Primary Examiner — T Chase Nelson*(74) Attorney, Agent, or Firm* — Pro-TECHTOR International Services; Ian Oglesby(57) **CLAIM**

The ornamental design for the tread for an outsole, as shown and described.

DESCRIPTION

FIG. 1 is a perspective view of the present tread for an outsole;

FIG. 2 is an enlarged, partial perspective view thereof;

FIG. 3 is an enlarged, partial front elevational view thereof;

FIG. 4 is a right side elevational view of the enlarged, partial portion seen in FIG. 3;

FIG. 5 is a left side elevational view of the enlarged, partial portion seen in FIG. 3;

FIG. 6 is a top plan view of the enlarged, partial portion seen in FIG. 3;

FIG. 7 is a bottom plan view of the enlarged, partial portion seen in FIG. 3; and,

FIG. 8 is a reference perspective view of a partial portion of the claimed design seen in condition of use on an outsole. The broken lines depict unclaimed portions of the outsole and environmental structure that forms no part of the claimed design.
